UNITED STATES PATENT OFFICE.

WILLIAM H. BOUST, OF AUDUBON, IOWA.

FIREARM.

No. 849,198.

Specification of Letters Patent.

Patented April 2, 1907.

Application filed January 24, 1906. Serial No. 297,678.

To all whom it may concern:

Be it known that I, WILLIAM H. BOUST, a citizen of the United States, residing at Audubon, in the county of Audubon, State of Iowa, have invented certain new and useful improvements in Firearms; and I do hereby declare the following to be a full, clear, and exact description of the invention, such as will enable others skilled in the art to which it appertains to make and use the same.

This invention relates to firearms, and has for its object to provide an arm equipped with means for producing a light and with means for throwing the light upon an object at which the firearm is aimed.

Another object is to provide an arm thus equipped and having also means for varying the size of the light thrown.

Other objects and advantages will be apparent from the following description.

In the drawings forming a portion of this specification and in which like numerals of reference indicate similar parts in the several views, Figure 1 is a side elevation of a revolver constructed in accordance with the present invention. Fig. 2 is a vertical longitudinal side section of the revolver. Fig. 3 is a cross-section on line 3 3 of Fig. 2, showing the means for revolving the shutter-shaft. Fig. 4 is a view showing the forward end of the revolver. Fig. 5 is a detail illustrating the shutter mechanism.

Referring now to the drawings, the present invention includes a firearm which is shown as a revolver having a grip 5, lock mechanism 6, and barrel 7. Beneath the barrel and extending longitudinally thereof there is a tube 8, having in its rearward end a lamp 9, the forward portion of the tube being detachable to give access to the lamp. The forward and rearward portions of the tube are indicated at 10 and 11, respectively, and are connected by a screw-joint 12, and at their mutually-adjacent ends these sections 10 and 11 have inwardly-extending annular flanges 10' and 11', respectively, which coöperate to receive and hold a lens 13 therebetween.

The handle 5 has a chamber 6' therewithin, and in this chamber there is located a battery 7', which is connected, by means of a wire 14, with the lamp 9. A push-button 15 is mounted in the handle for operation by the thumb of the user, and this push-button is connected with the battery by means of a wire 16 and with the lamp by means of a wire

It will thus be seen that the push-but-

ton may be operated to light the lamp, and the lens 13 is disposed, as shown, to project the light of the lamp through the end of the tube, the arrangement being such that the resultant spot of light is so projected with respect to the barrel that a shot fired from the barrel will strike in the center of the spot.

At the forward end of the tube 8 there is a shutter 18, which includes a supporting-ring 19, upon which are pivoted a plurality of leaves 20, having toothed outer ends 21, which mesh with an internal gear 22, the gear 22 having also external teeth 23, meshing with a pinion 24, carried by a shaft 25, which extends rearwardly within the tube, the arrangement being such that rotation of this shaft results in movement of the leaves, as will be readily understood, and these leaves, as will be seen from the drawings, operate to vary the size of the opening at the forward end of the tube and may be moved into position to completely cover this opening.

At its rearward end the shaft 25 has a small pinion 26, and meshing with this pinion there are a pair of transversely-extending rack-bars 27 and 28, which extend oppositely beyond the faces of the tube and in position for engagement of their outer ends by the fingers of the user of the arm. It will thus be seen that inward movement of one of these rack-bars will cause the shaft 25 to rotate in one direction to close the shutter, while inward movement of the other rack-bar will open the shutter.

The revolver includes a cylinder 29, having a pivot-shaft 30 movable into and out of the cylinder, and this shaft has rack-teeth 31, with which there meshes a pinion 32, carried by a laterally-extending shaft 33, having a thumb-wheel at its outer end, this thumb-wheel being operable to move the pivot-shaft into and out of the cylinder, as will be understood.

The revolver includes the usual metallic frame 34, in which the lock mechanism and other portions are mounted.

What is claimed is—

1. The combination with a firearm, of a tube carried thereby and including forward and rearward detachably-connected sections, flanges carried by the sections at their mutually-adjacent ends, a lens engaged between the flanges and lying within the tube, a lamp within the rearward section, and a shutter at the forward end of the tube.

2. In a revolver, the combination with a frame, of a revoluble cylinder mounted therein, a pivot-shaft slidably engaged in the cylinder and the frame for rotation of the cylinder in the frame, said pivot-shaft having rack-teeth thereupon, a pinion meshed with the rack-teeth, and a shaft carried by the pinion, said second-named shaft being arranged for rotation of the pinion to move the pivot-shaft into and out of the cylinder.
3. The combination with a firearm, of a tube carried thereby and having an open end,

a shutter for the open end, an operating-shaft for the shutter, a pinion carried by the operating-shaft, a transversely-extending rack-bar meshed with the pinion and movable to move the shaft, and a lamp within the tube.

In testimony whereof I affix my signature in presence of two witnesses.

WILLIAM H. BOUST.
